APPARATUS FOR PULSATION ELIMINATION
IN FLUID STREAMS

Foster M. Stephens, Los Angeles, and Cecil F. Yates, North Hollywood, Calif., assignors to The Fluor Corporation, Ltd., Los Angeles, Calif., a corporation of California

Application August 5, 1946, Serial No. 688,552

11 Claims. (Cl. 138—30)

1

This invention has to do with apparatus for the removal of pressure pulsations occurring in liquid streams, and relates particularly to improvements in certain type of systems disclosed in copending application Serial Number 631,192, filed November 27, 1945, on Pulsation elimination in liquid streams.

In certain of its major aspects, the invention relates to pulsation eliminating apparatus employing a pair of vessels communicable with the liquid-carrying line and containing gas which undergoes compression and expansion in response to the transmission respectively of increasing and decreasing line pressures. Basically, the general combination contemplates the provision of means, or an appropriate resistance, in the pulsating liquid line, for shifting the normal phases of the pulsations being transmitted to one of the chambers. Such resistance preferably, though typically, may take the form of an elongated restriction or inductance in the line between its connections with the gas-containing vessels.

One primary object of the invention is to provide a unitary assembly utilizing a body structure within which is accommodated the gas containing vessels and their line connections, as well as the restricted passage or inductance section of the line. Particularly the invention contemplates replacement of the vessels within the housing in a manner rendering them directly accessible for gas charging, while maintaining the remaining parts and connections in compact relation within the body.

A further object of the invention is to provide such connections and valve controls as will permit isolation of either or both vessels from the line, and withdrawal of liquid from the vessels so that the latter may be charged with gas at an accurately determinable base pressure.

All the features and objects, as well as the details of an illustrative embodiment of the invention, will be fully understood from the following description of the accompanying drawing which shows the apparatus in cross-section taken through the body.

Referring to the drawing, the apparatus comprises a tubular body 10, suitably mounted or supported, as by a pair of legs 11. Each end of the body carries a removable cover 12 secured to the body flanges 13 by bolts 14, each cover carrying an annular guard 15 for protection of the gas vessel fittings.

The body 10 contains a pair of gas-charged vessels 16, preferably of spherical form, having their outer or neck portions 17 received within

2

openings 18 in the covers 12. Each vessel 16 contains a bladder-like flexible diaphragm 19, shaped in accordance with the vessel so that when fully distended the diaphragm will conform to the spherical inner surface of the vessel. The neck of the diaphragm is secured to the vessel in any suitable manner, as by a clamping head 20 threaded into the vessel and containing a valve 21 through which gas may be charged into and maintained under a desired pressure within the diaphragm chamber 22. At this point it may be observed that the gas pressure in chamber 22 will be so related to the pressure in the liquid chamber 23 at the opposite side of the diaphragm, as to maintain the latter in a condition of deflection, for example as shown in the sectionally illustrated vessel, permitting displacements of the diaphragm causing compression and expansion of the gas in chamber 22, in response respectively to increasing and decreasing pressures in the liquid chamber 23.

Pipes 24 are illustrative of a line carrying liquid in a condition of pulsating flow, as created for example by piston type pump from which pressure pulsations are transmitted by the liquid stream. Pipes 24 have flange connections at 25 with closed end pipes 26 extending laterally through the wall of the body into its interior. The liquid chambers 23 in the vessel 16 are connected with the liquid line by way of pipes 27 each containing a valve 28, accessible through an opening 29 in the body, and a T-fitting 30 to which is connected the liquid draw-off line 31 carrying an outside valve 32.

The pipes 26 are in communication through a type of connection 33 presenting resistance to the liquid flow from one to the other of the pipes, and therefore imposing on the liquid stream a pressure drop in accordance with the nature of the resistance. As will later appear, this resistance may be one or different types (by analogy to electrical filter systems) although preferably it is made in the form of an inductive type resistance comprising an elongated pipe 34 of considerably smaller diameter than the line size, to present a restricted fluid passage 35. Being ordinarily of greater length than the distance between the pipes 26, pipe 34 may be formed as a coil extending about the pipes 26 and connecting 36 therewith, substantially as shown.

The vessels 16 serve essentially as variable liquid volume capacitances exerting converting influences on the pulsations transmitted by the liquid flowing in the line 24. This converting effect results from the ability of the capacitance, be-

cause of its responsiveness to increasing or decreasing liquid pressure, to exert a phase shifting influence on the line stream pulsations by presenting to each positive pulse, a reduced or negative compensating pressure, and to each negative pulse an increased or positive compensating pressure. With the phases thus compensated, the tendency is toward regularization of the liquid stream pressure.

The characteristic effect of the resistance 33 is to effect a pressure drop in the liquid stream, and to function in relation to the capacitances 16, toward further dissipation of the pulsations. A resistance as such, taking into account only its pressure reducing function, may take the form of various kinds of restrictions. It is preferred, however, to employ a resistance, specifically an inductance type resistance, which may be predetermined to exert a pulsation phase shifting effect, thus introducing a time factor in the phase sequence. Briefly, the general effect of the inductance type restriction is to create a kinetic energy condition retarding, for example, a positive pressure surge while simultaneously increasing the stream velocity, and the discharge of the accelerated stream into the capacitance chamber so that the resulting energy of the phase-shifted pulse coincides with a negative pressure condition or pulse in the chamber, to produce an average or substantially constant resultant pressure. The length and diameter of the inductance connection may be varied in accordance with the particular requirements of individual installations.

As a typical example, the apparatus as shown in the drawing has effectively eliminated pulsations from a liquid stream being discharged through line 24 at the rate of about 50 cycles per minute by a piston type pump operating at a frequency of 25 strokes per minute. The capacitance 16 formed by spherical shells of 8 inches outside diameter, and the inductance connection 33 consisted of a 1 inch pipe 34 having a length of 6 feet.

Valves 28 may be closed when for any reason it is desired to isolate the capacitances from communication with the liquid line. Provision is made by the valve lines 31 for withdrawing all liquid from the chambers 23, or for relieving the pressure at the liquid side of the diaphragms, so that the chambers 22 may be charged with gas at accurately determinable pressure, initially resulting in deflection of the diaphragm into full spherical surface engagement with the under-surface of the vessel. Thereafter, when valves 32 are closed and valves 28 opened, the diaphragms assume an intermediate state of deflection to a degree depending upon the pressure differentials between the chambers 22 and 23.

We claim:

1. Apparatus for eliminating pulsations in a liquid stream flowing continuously through a line, comprising a housing, a pair of vessels contained in said housing, means connecting said vessels with said line at spaced locations therealong, said vessels containing gas which compresses and expands in response to increasing and decreasing pressures transmitted through the liquid from said line, and means providing a restriction in said line between said locations.

2. Apparatus for eliminating pulsations in a liquid stream flowing continuously through a line, comprising a housing, a pair of vessels contained in said housing, means connecting said vessels with said line at spaced locations therealong, said

vessels containing gas which compresses and expands in response to increasing and decreasing pressures transmitted through the liquid from said line, and an elongated tube forming a restricted passage in the line between said locations.

3. Apparatus for eliminating pulsations in a liquid stream flowing continuously through a line, comprising a housing, a pair of vessels contained in said housing, means connecting said vessels with said line at spaced locations therealong, said vessels containing gas which compresses and expands in response to increasing and decreasing pressures transmitted through the liquid from said line, means providing a restriction in said line between said locations, valve means in the housing for closing communication between the line and said vessels, and means for withdrawing liquid from the vessels with said valve means closed.

4. Apparatus for eliminating pulsations in a liquid stream flowing continuously through a line, comprising a housing, a pair of vessels contained in the housing, each vessel containing a diaphragm and at one side of the diaphragm a chamber containing gas which compresses and expands in response to deflections of the diaphragm, means connecting said vessels at the other sides of their diaphragms with said line at spaced locations therealong, and means providing a restriction in the line between said locations.

5. Apparatus for eliminating pulsations in a liquid stream flowing continuously through a line, comprising a housing, a pair of vessels contained in the housing, each vessel containing a diaphragm and at one side of the diaphragm a chamber containing gas which compresses and expands in response to deflections of the diaphragm, means connecting said vessels at the other sides of their diaphragms with said line at spaced locations therealong, means providing a restriction in the line between said locations, and fittings carried by said vessels at locations accessible at the outside of the housing for charging gas under pressure into said chambers.

6. Apparatus for eliminating pulsations in a liquid stream flowing continuously through a line, comprising a housing, a pair of vessels contained in the housing, each vessel containing a diaphragm and at one side of the diaphragm a chamber containing gas which compresses and expands in response to deflections of the diaphragm, spaced pipes extending through the side of said housing and connecting said vessels at the other side of their diaphragms with said line, and an elongated tube connecting said pipes and forming a restricted passage in the line, said tube being longer than the distance between said pipes.

7. Apparatus for eliminating pulsations in a liquid stream flowing continuously through a line, comprising a housing, a pair of vessels contained in the housing, each vessel containing a diaphragm and at one side of the diaphragm a chamber containing gas which compresses and expands in response to deflections of the diaphragm, spaced pipes extending through the side of said housing and connecting said vessels at the other side of their diaphragms with said line, an elongated tube contained in the housing and connecting said pipes and forming a restricted passage in the line, said tube being longer than the distance between said pipes, fittings carried by said vessels and accessible from the outer ends of the housing for charging gas under pressure into said chamber, valves in the housing for closing com-

munication between said vessels and pipes, and valve controlled means operable when said valves are closed to withdraw liquid from said vessels.

8. Apparatus for eliminating pulsations in a liquid stream flowing continuously through a line, comprising a vessel containing a diaphragm and at one side of the diaphragm a closed chamber containing gas which compresses and expands in response to deflections of the diaphragm, a pipe connecting said vessel at the other side of the diaphragm with said line, a fitting through which said chamber is chargeable with gas, a normally open valve in said pipe for closing communication between said vessel and line, and means for withdrawing liquid from said vessel when said valve is closed.

9. Apparatus for eliminating pulsations in a liquid stream flowing continuously through a line, comprising a pair of vessels each containing a diaphragm and at one side of the diaphragm a closed chamber containing gas which compresses and expands in response to deflections of the diaphragm, pipes connecting said vessels at the other sides of their diaphragms with locations along said line, means restricting the liquid flow in the line between said locations, and normally open valves in said pipes for closing communication between said vessels and line.

10. Apparatus for eliminating pulsations in a liquid stream flowing continuously through a line, comprising a pair of vessels each containing a diaphragm and at one side of the diaphragm a closed chamber containing gas which compresses and expands in response to deflections of the diaphragm, pipes connecting said vessels at the other

5 sides of their diaphragms with locations along said line, means restricting the liquid flow in the line between said locations, normally open valves in said pipes for closing communication between said vessels and line, and means for withdrawing liquid from said vessels when said valves are closed.

11. Apparatus for eliminating pulsations in a fluid stream flowing continuously through a line, comprising a shell containing a pair of chambers, means forming passages for connecting said chambers with said line at spaced locations therealong, said chambers being substantially closed except for said connections and containing gas which compresses and expands in response to increasing and decreasing pressures transmitted through said passages from the fluid in said line, and an elongated pipe contained in said shell and forming a restricted passage in the line between said locations, said pipe being substantially longer than the distance between said locations.
